UNITED STATES PATENT OFFICE.

CHARLES S. DAY, OF WAVERLY, MARYLAND.

MILL FOR HULLING CORN.

SPECIFICATION forming part of Letters Patent No. 313,997, dated March 17, 1885.

Application filed April 1, 1884. (No model.)

To all whom it may concern:

Be it known that I, CHARLES S. DAY, of Waverly, in the county of Baltimore and State of Maryland, have invented certain Improvements in Mills for Hulling Corn, of which the following is a specification.

In the accompanying drawings, forming a part hereof, Figure I is a longitudinal section of the improved mill. Fig. II is a cross-section of Fig. I taken on the dotted line *x x*. Figs. III to IX, inclusive, are views of parts of the invention on an enlarged scale.

A is a cylindrical casing or shell supported in any suitable manner on a frame, B.

C is a revoluble shaft extending entirely through the casing A, having bearings *a*, which rest in boxes *b* on the frame B. The portion of the shaft C inclosed within the shell A is grooved longitudinally from one end to a point near the other, and the grooves, which are denoted in the drawings by *c*, are dovetailed, or wider at their bottom than at the surface of the shaft.

D are knives adapted to fit in the grooves *c*, and E are blocks inserted in the said grooves to separate the knives, as shown in Figs. I, VIII, and IX. The knives D and the separating blocks E in each groove *c* are secured together by a bolt, F, which is passed through them, its head resting in a pocket in a lug which closes one end of the groove. The arrows shown in

Fig. II indicate the direction of revolution of the shaft C. The front edge and the periphery of the knives have saw-teeth, which, as the shaft is revolved rapidly in the casing A and among the corn with which the said casing is filled, scrape the hull or outer covering from the corn, which escapes from slots *d* near the bottom of the casing. The corn is fed to the mill through a hopper, G, and the hulled product is removed from the casing, after the completion of the hulling process, through an opening, *e*, which is provided with a door, *f*. The hulled corn and the hulls or waste product fall to the floor or to any suitable receptacles placed under the mill, and are separated by a partition, *g*.

I claim as my invention—

In a mill for hulling corn, a stationary shell combined with a revoluble shaft, the said shaft having longitudinal dovetail grooves open at one end and closed at the other, and at the closed ends provided with pockets, a series of knives and separating blocks in the grooves, and bolts which pass through the said knives and blocks, each having a nut at one end and a head at the other, the said heads resting in the said pockets, substantially as specified.

CHARLES S. DAY.
